UNITED STATES PATENT OFFICE.

JOSEPH F. HITCHCOCK, OF ROCHESTER, NEW YORK.

STOP MECHANISM.

1,268,008.

Specification of Letters Patent. Patented May 28, 1918.

Application filed March 19, 1917. Serial No. 155,681.

To all whom it may concern:

Be it known that I, JOSEPH F. HITCHCOCK, of Rochester, in the county of Monroe and State of New York, have invented certain new and useful Improvements in Stop Mechanisms; and I do hereby declare the following to be a full, clear, and exact description of the same, reference being had to the accompanying drawings, forming a part of this specification, and to the reference characters marked thereon.

My invention has for its object to afford a structure for sound reproducing machines, with more particular reference to mechanisms of the disk or flat record type and the specific purpose of my improvement is to provide for automatically bringing the record to a standstill at any predetermined point in its operation. In a more particular aspect my invention is designed with a view to employing the fewest possible number of parts, and so inter-relating them that the mechanism can be instantly and readily set to stop the machine precisely at the end of the reproducing part of the record, or at any intermediate point in the playing of the record. To these and other ends the invention consists in certain improvements and combinations of parts, all as will be herein-after more fully described, the novel features being pointed out in the claims at the end of the specification.

In the drawings:

Figure 1 is a plan view showing the application of my improvements to a conventional type of sound reproducing machine;

Fig. 2 is an enlarged bottom plan view of the stop mechanism with the parts in the position they assume when the brake is applied;

Fig. 3 is a similar view with the parts in the position they assume when the brake is released;

Fig. 4 is a similar view showing the position of the parts while being adjusted, when the controlling arm is free for movement to any position of the tone arm;

Fig. 5 is a side elevation of the parts illustrated in Fig. 3;

Fig. 6 is a sectional view on the line 6^a—6^a of Fig. 3;

Fig. 7 is an enlarged bottom plan view of a modified form, showing the brake applied;

Fig. 8 is a similar view with the brake released;

Fig. 9 is a view similar to Fig. 7 with the parts differently adjusted;

Fig. 10 is a view similar to Fig. 8 with the parts adjusted as in Fig. 9;

Fig. 11 is a plan view of the adjusting means for timing the release, and

Fig. 12 is a sectional view on line 12—12 of Fig. 11.

Similar reference characters throughout the several views indicate the same parts.

The invention may be carried out in a variety of ways, being applicable not only to the various types of spring motor and other mechanically driven types, but also to electrically driven machines as well, where it is desirable to stop operation of the motor at any instant, and by way of illustration I have shown one adaptation of my improvements practically as applied to a disk record type of apparatus. 1 designates the usual table or rotary support, while 2 is a record arranged thereon and 3, the swinging tone arm carrying a suitable projection 4 that actuates the stop mechanism in a manner that will presently appear more fully.

5 is a brake in the form of a shoe arranged for engagement with the inner surface of the flange or shoulder 6 on the table 1, and the brake is mounted on a brake lever 7 which is preferably pivoted at 8 or may be otherwise movably mounted so as to permit it to be withdrawn from braking position to its released position as indicated in Fig. 3. The brake lever 7 is provided with a notch or shoulder 9 with which co-operates a retaining latch 10 that is pivotally mounted at 11, and 12 is a spring connecting the outer end of the brake lever with the latch 10 and tending to move said parts normally to the position shown in Fig. 2, where the brake lever is in engagement with the record table or support and the latch is in engagement with the brake lever. Movement of the latch in the opposite direction is prevented by the stationary pin or stop 12^a.

13 is a setting lever mounted co-axially with reference to the brake lever 7 and arranged when moved to the left of Fig. 2 to engage a flange or projection 14 on the brake lever 10 and move the latter to the position shown in Fig. 3, or until the latch 10 engages over the notch or shoulder 9 to retain the brake lever in released position. Connected to the latch 10 is a link 14^a which is in turn connected to the inner end of a controlling arm 15, while the latter is pivotally mounted at

16 upon a suitable carrier 17 that is also pivotally mounted upon the base upon an axis that coincides with the axis 18 when the parts are in the position of Fig. 2, so that 5 the arm can be adjusted without changing the position of the latch, and at the same time permitting movement of the latch to vary the position of the arm. The several parts of the stop mechanism already described as well as those which are to be set forth later are mounted upon a base plate 10 which is suitably attached to the top of the frame 20 underneath the rotary table as shown in Fig. 1. 22 designates a spring 15 having one end connected to a post 23 and its opposite end to the carrier 17 and acting with a tendency to move the latter to the right from the position shown in Fig. 2, when released as indicated in Fig. 4. The 20 carrier 17 is normally held against any such movement, and to this end it is provided with a concentric gripping surface 24 which cooperates with a friction lock 25. The latter is preferably in the form of a lever 25 pivoted about the axis 23 and having a curved surface 26 which frictionally engages the aforementioned gripping surface on the carrier. Friction lock 25 is slotted at 27 for engagement with a pin or projection 30 which limits its movement in opposite directions and 29 is a leaf spring engaging the outer end of the friction lock and acting to move the latter normally into gripping relation with the carrier as shown 35 in Fig. 2. The friction lock is moved against the action of the spring 29 in order to release the carrier 17, by the setting lever 13 which is moved to the right from the position shown in Fig. 2. With such operation 40 the inner end or tail portion 30 of the setting lever engages the adjacent surface 31 of the friction lock causing the latter to swing inwardly about its axis 23 as shown in Fig. 4. This releases the friction lock 45 from engagement with the carrier 17 permitting the latter and also the controlling arm 15 to swing to the right under the action of the spring 22. After the parts are set to their respective positions, as shown 50 for instance in Fig. 3, if the outer end of the controlling arm is moved to the left of said figure, the latch 10 is swung to the right permitting the brake lever to move the brake into engagement with the record table. 55 The operation of the mechanism may be described briefly as follows: Starting with the parts in the position shown in Fig. 2, upon placing a record upon the table, the tone arm is adjusted manually to the end of 60 the playing portion of the record. The setting lever 13 is then moved to the right with reference to Fig. 2, causing the friction lock 25 to move away from the carrier 17, after which the spring 22 actuates the carrier 17 65 and the controlling arm 15 to the right with reference to Fig. 2 until the controlling arm is in engagement with the stop or projection 4 on the tone arm. The brake is then released by throwing the setting lever 13 to the left of the position shown in Fig. 2, 70 actuating the brake lever to the position shown in Fig. 3 where it is retained by the latch 10, and the slight movement of latch 10 necessary to engage the brake lever, causes a corresponding slight movement of the arm 15, so that the latter will be engaged slightly in advance of the position to which it is preliminarily set, and thus insures stopping the mechanism, by withdrawing the latch fully, when playing of the record is 75 completed. The tone arm is then set to starting position and the operation of the machine commenced. When the tone arm, in its progress over the record, shall have nearly reached the predetermined position 80 of adjustment, its projection 4 engages the controlling arm 15 and moves the latter to the left with reference to Fig. 3, that is to say, the outer end of the tone arm is moved to the left about the axis 16. This causes 85 the latch 10 to be swung away from the brake lever as shown in Fig. 2, until it entirely disengages the shoulder 9, entirely releasing the brake lever which is thereupon forced into engagement with the rotary table 90 by the spring 12. This same latch mechanism and arrangement of controlling arm may likewise be applied to an electrically controlled instrument by arranging for governing the electric circuit through the movements of the latch. It is sometimes desirable to provide for stopping the record either in advance of or after the end of the playing portion is reached, and to accomplish this, I afford an adjusting means for 95 varying the relation of the initial position to which the controlling arm is set with the position at which the record is stopped, or in other words, varying the additional movement or overthrow of the controlling 100 arm, subsequently to its initial setting, which is caused by movement of latch 10 into locking engagement with the brake lever. This is accomplished by an adjustable member or plate 40 mounted on brake lever 7, as seen 105 in Figs. 7 to 12 inclusive. The member 40 is adjustable by a slot 41 and screw 42 and carries a projection or end portion 43 which engages the latch 10, when adjusted outwardly, as shown in Figs. 7 and 8. The 110 brake lever 7 is cut away to afford a recess 44, into which the latch 10 projects, when the adjustable plate 40 is moved inwardly as shown in Figs. 9 and 10. Assuming the plate 40 to be adjusted as in Figs. 7 and 8, 115 and that the arm 15 has been adjusted against the tone arm projection 4, when the setting lever is moved to release the brake lever as shown in Fig. 8, the controlling arm 120 moves from the position shown in dotted 125 130

lines to that shown in full lines. This causes the arm 15 to be engaged by the tone arm projection 4 early with reference to the end of the playing portion, or in advance 5 of the end of the playing portion. By adjusting the parts as shown in Figs. 9 and 10 with the plate 40 withdrawn, the overthrow of the controlling arm when the latter is engaged with the brake lever, is slight, as indicated by the dotted and full lines of the projection 4 in Fig. 10, so that stopping of 10 the record, with reference to the end of its playing portion is delayed or retarded. Thus, by adjusting the plate 40 outwardly, 15 the stopping operation is made earlier, with reference to the selected position of the tone arm on the record, and by adjusting the plate 40 inwardly, the stopping operation is delayed. In the modified arrangement of 20 the figures just described, the brake lever and latch are actuated by separate springs 45 and 46 respectively.

I claim as my invention:

1. In a stop mechanism for sound reproducing apparatus, the combination with a 25 brake and movable brake lever, of a movable retaining latch arranged to coöperate with the brake, an adjustable spring actuated controlling arm connected to the latch, a friction lock acting to hold the controlling arm in adjusted position, and a setting lever operatively associated with the brake lever and the friction lock and acting both to release the friction lock and to move the brake 30 lever to released position.

2. In a stop mechanism for sound reproducing apparatus, the combination with a 35 brake and movable brake lever, of a movable retaining latch arranged to coöperate with the brake lever, an adjustable spring actuated controlling arm connected to the latch, a friction lock acting to hold the controlling arm in adjusted position, and a setting lever operatively associated with the 40 brake lever and the friction lock and affording means for alternately releasing the friction lock and moving the brake lever to released position.

3. In a stop mechanism for sound reproducing apparatus, the combination with a 45 brake and movable brake lever, of a movable retaining latch arranged to coöperate with the brake lever, an adjustable spring actuated controlling arm connected to the 50 latch and adjustable without changing the position of the latch, a friction lock acting to hold the controlling arm in adjusted position and a setting lever operatively associated with the brake lever and the friction lock and affording means for alternately releasing the friction lock and moving the 55 brake lever to released position.

4. In a stop mechanism for sound reproducing apparatus, the combination with a 60 brake and movable brake lever, of a mov-

able retaining latch arranged to coöperate with the brake lever, an adjustable spring actuated controlling arm connected to the latch and adjustable without changing the position of the latch, a friction lock acting 70 to hold the controlling arm in adjusted position and a setting lever operating when moved in one direction to release the friction lock and when moved in the opposite direction to move the brake lever to released position where it is engaged by the latch.

5. In a stop mechanism for sound reproducing apparatus, the combination with a 75 brake and movable brake lever, of a movable retaining latch arranged to coöperate with the brake lever, a spring actuated pivoted carrier having a gripping surface, a spring actuated arm pivotally mounted on the carrier and connected to said latch, a 80 spring controlled movable friction lock having a curved surface engaging said gripping surface on the carrier, and a movable setting lever acting when moved in one direction to engage and move the friction lock 85 and when oppositely moved, to engage and effect movement of the brake lever.

6. In a stop mechanism for sound reproducing apparatus, the combination with a 90 brake and pivoted brake lever, of a pivoted retaining latch arranged to engage and hold the brake lever in released position, a spring actuated pivoted carrier having a concentric gripping surface, a spring actuated arm pivotally mounted on the carrier, a link 95 connecting said arm and said latch, a spring controlled pivoted friction lock having a curved surface adapted to frictionally engage said concentric surface on the carrier to hold it against movement, a setting lever 100 pivoted coaxially of the brake lever and movable into engagement with the free end of the friction lock, and a projection on the brake lever located in the path of the setting lever when the latter is moved in the 105 opposite direction to the friction lock.

7. In a stop mechanism for sound reproducing apparatus, the combination with a 110 movable latch, an adjustable spring actuated controlling arm connected to the retaining latch, a friction lock acting to hold the controlling arm in adjusted position, and a setting lever operatively associated with the friction lock.

8. In a stop mechanism for sound reproducing apparatus, the combination with a 115 movable latch, of an adjustable spring actuated controlling arm connected to the latch, and adjustable without changing the position of the latch, a friction lock acting to 120 hold the controlling arm in adjusted position, and a setting lever operatively associated with the friction lock.

9. In a stop mechanism for sound reproducing apparatus, the combination with a 125

4

pivoted latch, of a spring actuated carrier having a concentric gripping surface, a spring actuated arm pivotally mounted on the carrier, a connection between said arm and said latch, a spring controlled pivoted friction lock having a curved surface adapted to frictionally engage said concentric surface on the carrier to hold it against movement, and a setting lever movable into engagement with the free end of the friction lock.

10. In a stop mechanism for sound reproducing apparatus, the combination with a

brake and movable brake lever, of a movable retaining latch coöperating with the 15 brake lever, an adjustable member on the brake lever coöperating with the latch to vary the position thereof when the brake lever is released, an adjustable spring actuated controlling arm connected to the latch 20 and having its position controlled thereby, and a lock governing the adjustable controlling arm and acting to hold it in adjusted position.

JOSEPH F. HITCHCOCK.
